SYSTEM OF LIGHTING AND LIGHTING UNIT
FOR USE THEREINHarold F. Lorenz, Meriden, Conn., assignor to
The Miller Company, Meriden, Conn., a corpora-
tion of Connecticut

Application November 5, 1940, Serial No. 364,339

5 Claims. (Cl. 240—9)

The present invention relates to a system of lighting and lighting units for use therein, and is more particularly directed toward a lighting system suitable for illuminating the working areas on the opposite sides of parallel aisles.

In textile mills and factories employing batteries of machines on opposite sides of parallel aisles it is important to place a high intensity of illumination on the machines and to satisfactorily illuminate the aisle between the machines. This is usually done by some form of asymmetric equipment placed over the center of the aisle. The present invention contemplates lighting equipment for this purpose wherein each unit over the center of the aisle employs two fluorescent light sources each associated with a parabolic reflector whose axis is tilted at the proper angle to produce a sloping beam for illuminating the machine on the side of the aisle opposite the reflector.

Asymmetric lighting equipment which would provide satisfactory lighting for the machines on opposite sides of a single aisle may have a substantial amount of light spilled at higher angles than necessary for illuminating the working areas, and this high angle spilled light falls on the machinery of adjacent aisles. This spilled light is useful for illuminating purposes, and the present invention contemplates designing the lighting systems so that this spilled light does not escape at sufficiently high angles to reach the normal eye level of the operator in the adjacent aisle. By providing suitable cut off angles in the reflectors employed it is possible for the operator to have the eye completely shielded so as to receive no annoying glare from the fixtures over adjacent aisles.

Other and further objects of the invention will appear as the description proceeds.

The accompanying drawings show, for purposes of illustrating the present invention, an embodiment in which the invention may take form, it being understood that the drawings are illustrative of the invention rather than limiting the same.

In these drawings:

Figure 1 is a perspective view of a lighting unit;

Figure 2 is a transverse sectional view of the same with parts in elevation;

Figure 3 is a longitudinal sectional view of the lighting unit with parts in section; and

Figure 4 is a diagrammatic view illustrating the employment of the lighting units in a sys- 55

tem for illuminating working areas on opposite sides of parallel aisles.

The lighting unit shown has a suspension 10 by which it may be supported from above.

5 Two fluorescent lamps 11 and 12 are supported in conventional fluorescent lamp holders 13 and 14 carried on end plates 15. The lamps 11 and 12 are received in parabolic reflectors 16 and 17, these being secured to the end plates and to one another as indicated in the drawings. These reflectors have axial planes indicated at 20, 20 which slope at substantially 30° to the vertical and the parallel light rays 20a, 20b are directed downwardly, as indicated in the drawings, at substantially 30° to the vertical. The axial plane or center line of the concentration 20 is indicated in Figure 4. By mounting the fixtures at the proper height above working areas, illustrated at W in Figure 4, it will be apparent that the beams 20 from the parabolic reflectors may be directed toward the working areas.

15 The lower edges 21 of the reflectors 16 and 17 are substantially below the centers of the light sources 11 and 12 and are spaced slightly farther apart than the light sources. The highest angle direct light which can escape from the bottom of the light sources is in each instance indicated by the ray 22. When this ray is drawn in on Figure 4, it will be seen that the lighting unit in 20 the left aisle produces direct light which spreads over the machines in the right aisle. The normal eye level of the operator is indicated by the eye E in Figure 4, and this in each instance is above the ray 22. Hence the operator does not 25 see the bright sources of the lighting unit in the adjacent aisle. As the lower edges 21 are more widely spaced than the light sources, it is also obvious that the limiting direct ray from the light source adjacent the edge of the reflector is 30 rather steep, as indicated at 23. The dominant rays from the sources escaping past the lower edges of the reflector are indicated by the lines 24, 24a, and these lines are at substantially 90° to one another.

35 With the arrangement shown not only is the dominant output of the unit placed on the working areas, but a substantial amount of direct light from each source falls in the aisle under the unit and a lesser amount falls on the machines in adjacent aisles. This produces a well diffused illumination on the various surfaces of the machine and on operations carried on in the machines, so that all parts and operations may be well lighted.

40 It is apparent that, within the scope of the in-

vention, modifications and different arrangements may be made other than is herein disclosed, and the present disclosure is illustrative merely, the invention comprehending all variations thereof.

What is claimed is:

1. A system of lighting for illuminating working areas on the two opposite sides of parallel aisles, comprising parallel lighting units placed at the same height above the working areas over the centers of the aisles, each lighting unit having two parallel light sources at the same elevation, each source being disposed along the focal line of a rectilinear reflector of substantially parabolic cross section with its axial plane tilted to direct the reflected rays across the vertical plane through the center of the corresponding aisle and toward the working area on the opposite side of said aisle, the lower portions of each of said reflectors acting as light shields to limit the maximum angle above the nadir through which direct light may be emitted so as to be below normal eye level in the adjacent aisle.

2. A system of lighting such as claimed in claim 1, wherein the lower edges of the reflectors are spaced slightly wider than the light sources so that direct light from each source may be emitted at a predetermined small angle from the other side of the nadir for aisle illumination.

3. A system of lighting for illuminating working areas on the two opposite sides of parallel aisles, comprising parallel light units placed at the same height above the working areas over the centers of the aisles, each lighting unit having two parallel light sources at the same elevation, each source being disposed along the focal line of a rectilinear reflector of substantially parabolic cross section with its axial plane tilted at an angle of approximately 30° to the vertical to direct the reflected rays across the vertical plane through the center of the corresponding

aisle and toward the working area on the opposite side of said aisle, the lower portions of each of said reflectors acting to limit the spread of direct light to substantially 90° and acting as light shields to limit the maximum angle above the nadir through which direct light may be emitted so as to be below normal eye level in the adjacent aisle.

4. A direct lighting unit adapted for mounting over the center of an aisle for similarly illuminating working areas on the opposite sides of the aisle, comprising two parallel horizontal long light sources, spaced a substantial distance apart and at the same level, an inwardly facing, open mouthed, parabolic, rectilinear reflecting trough about each source, each trough being symmetrical about a downwardly sloping axial plane directed toward the working area on the opposite side of said aisle and producing a downwardly sloping beam of reflected light, the beams crossing midway between the sources so that an aisle area below the unit receives direct light mixed with diffusely reflected light, the lower edges of the reflecting troughs being spaced substantially below their upper edges and below the sources and forming light shields each of which screens the opposite source to a predetermined angle below the horizontal and limits the direct light from the corresponding source to predetermined angles from the nadir, whereby the area to one side of the aisle receives reflected light and direct light from the opposite source and the immediate, but more remote area, receives direct light only from said opposite source.

5. A unit such as claimed in claim 4, wherein the slope of the axial planes of the reflecting troughs is substantially 30° from the vertical and the angle through which direct light escapes from each source is substantially 90°.

HAROLD F. LORENZ.
